(57) **CLAIM**

I claim the ornamental design for a door frame hanger, as shown as described.

DESCRIPTION

FIG. 1 is a front elevational view of a door frame hanger showing my new design;

FIG. 2 is a left side elevational view thereof, the right side elevational view being a mirror image thereof;

FIG. 3 is a top plan view thereof;

FIG. 4 is a rear elevational view thereof;

FIG. 5 is a bottom plan view thereof;

FIG. 6 is a front perspective view thereof; and,

FIG. 7 is a left side elevational view thereof, shown in the environmental use.

The broken lines environment is for illustrative purpose only and forms no part of the claimed design.
